UNITED STATES PATENT OFFICE

1,972,038

MUSICAL INSTRUMENT PLAYER

John W. Bissett, Garrison, Pa.

Application October 23, 1933, Serial No. 624,863

4 Claims. (Cl. 84—321)

In the customary way of playing stringed instruments where the strings are plucked or picked by the thumb and fingers as in the mandolin, for example, there is considerable fatigue or tiring of the wrist, thumb and fingers. Again there is a limit to the speed with which the picking can be done which restricts the scope of the music. Greater speed means an increase in the range of the musical composition. With these considerations in mind, I have produced a player for stringed instruments which will obviate the disadvantages mentioned and which will have other advantages and which will result in no loss of the musical quality of the performance. As one example of my invention, I will show in the drawing and describe hereinafter its application to or embodiment in a mandolin. My invention, however, consists in whatever is described by or is included within the terms or scope of the appended claims.

In the drawing:

Fig. 1 is a perspective view of enough of a mandolin to show that embodiment of my invention;

Fig. 2 is a vertical section of the player attachment at the tail piece end of the instrument;

Fig. 3 is a perspective view of a portion of one of the rollers and one of the picks separated.

Briefly described, my invention includes a series of parallel rollers, one for each string of the instrument and a vibratory picker adapted to be actuated by each roller, the rollers being rotatable by friction contact with the peripheries thereof as by means of a longitudinally reciprocating member corresponding with the bow of a violin. Because of the feasibility of using a bow-like operating device, a musician accustomed to playing the violin type of instrument is able instantly to play an instrument embodying or equipped with my invention.

The portion of the conventional mandolin 10, shown requires no special description as my invention involves no alteration in the structure thereof, my invention in fact being designed to employ or be available for use with a mandolin without any alteration of its essential characteristics.

Straddling the four strings 11, is a chassis or frame which includes a pair of spaced apart longitudinally extending base plates 12, by which the frame may be clamped or otherwise suitably secured to the table or front 13, of the instrument and upwardly arched cross bars 14, one at each end that extend transversely of the instrument and are arched so as to clear the strings below

them and which support and journal four parallel rollers 15, one above each string which rollers by friction contact with their peripheries may be rapidly revolved and preferably as has been explained, by a bow-like device. To enable individual rotation of each roller, a transverse line passing through their axes curves or arches upward and thereby each roller may be independently revolved by the bow.

Each roller has its periphery longitudinally ribbed or grooved to afford a good friction surface.

At each end each roller has a pintle 16, journaled to turn freely in a bearing in each end plate or bar 14, and preferably the upper part of the bar is a cap 17, that is secured in place by suitable bolts and preferably an oil hole runs through the cap to the pintle journaled in the underside of the cap.

On each pintle 16 nearest the picking point of the strings is a crank 18 that engages a radially extending slot 19 at one end of a finger 20, that constitutes the string pick and which is mounted between its ends on a pivot 21, projecting from the adjacent cross bar 14, so that the pick end 22, of the arm which is adjacent one of the instrument strings will vibrate as the crank rotates from the rotation of its roller and thus the string will be struck, plucked, or picked and caused to vibrate to give the required musical sound; and this, of course, is the case as to each of the strings.

Of course, the adjacent picks are sufficiently spaced from each other so that each will vibrate freely without obstruction from the other.

The outer ends of the pick pivots 21 are fitted each in a hole in a cross bar 23, which extends over the outer sides of the lower portions of the pick fingers 20 and at its opposite ends is secured as by means of screws to the side of the arm or bar 14. To make a smooth or even finish, the side of the bar 14 adjacent the radial member of the crank 18 is recessed to receive the crank arm and provide a space for its rotation or oscillation.

One of the roller journaling cross bars 14 may be rigidly or immovably a part of the frame while the provision is made in the case of the other for limited vertical movement or adjustment of the pick carrying part thereof, that is to say, the part along side of which the picks project towards the strings. However, as shown, both are adjustable. Accordingly, each cross bar is made of two pieces one 24, of which is of arched plate form with a vertical leg 25, at each side which lies against a corresponding portion of the cross bar 14 that is fixed to the base bars 12, and a sliding connec-

tion is provided at each leg that includes a bolt 26, and a vertical slot 27, which permit vertical movement through a limited extent of the roller journal carrying part of the plate and of the picks. Normally the vertically movable member 24, of the cross bar 14, is yieldingly held at its highest position by the pressure of a bent spring 28 that arches or bows downward from its opposite ends which bear against the bottom of said member 24, and at mid-length is engaged at the bottom by a screw adjustable bearing 29 so that the tension of the spring may be adjusted. By proper downward pressure of the bow in bowing, it will be seen that the movable member 24, of the cross bar may be depressed carrying with it the picks and upon release of that pressure, it will rise and that it is possible to have a delicate graduated downward movement by skillful pressure of the bow on the rollers and thus the quality or volume of the sound produced by the picks may be altered.

Preferably at each side the movable member 24 has a guide lug 30, that slidably bears against the adjacent stationary portion of the cross bar 24, and thereby the described vertical movement is a guided one.

The bow 31 may in length and general form correspond with a violin bow except preferably the roller engaging portion 32 of the bow is a satisfactory friction giving material such as a strip of rubber or the like suitably secured to the body or shank of the bow from end to end between the handle and the heel thereof.

It will give an understanding of the speed with which the picks may be vibrated to state that if the bow is thirty inches long and the bow-engaged rollers are each three-eighths of an inch in diameter, then one complete stroke of the bow would

revolve the roller twenty-six times so that in a period of about one and one-half seconds, the strings would be struck fifty-two times in one stroke of the bow. Thus a speed of vibration of the strings is possible that is impossible with the ordinary finger playing and this greatly enlarges the musical scope of the instrument. And, of course, the fatigue incident to finger picking or plucking is eliminated.

Of course, to avoid marring the delicate finish of the instrument, pieces of felt or other cushioning material may be positioned between the chassis or frame and the part of the instrument to which it is attached.

What is claimed is:

1. A stringed musical instrument player comprising plural vibratory string-engaging picks, roller-type actuating means for said string-engaging picks adapted to be turned by peripheral contact therewith and comprising a roller for each pick, and a bow reciprocable in peripheral contact with such roller-type actuating means.

2. A stringed musical instrument player comprising a group of rollers corresponding in number with the number of the strings to be vibrated, means supporting said rollers out of contact with the strings, and a vibratory pick operatively connected with each roller, said rollers being rotatable by contact of rotating means with the periphery thereof.

3. A player as in claim 2 in which each pick is a finger pivoted between its ends and the operative roller connection is a crank and slot.

4. A player as in claim 2 in which the picks are yieldably supported for movement towards and from the strings.

JOHN W. BISSETT.
